TROUSERS HANGER

Joseph D. McOsker, Allston, Mass.

Application July 7, 1939, Serial No. 283,268

2 Claims. (Cl. 223—96)

This invention relates to improvements in garment hangers, being especially directed to hangers for trousers. The ordinary type of garment hanger includes a cross bar over which the legs 5 of the trousers are hung. Inasmuch as this cross bar comprises a thin wire in the majority of instances, it follows that there is a noticeable crease when the garment is removed from the hanger.

This objectionable feature is overcome herein 10 by a novelty in the construction of the improved hanger, and the latter also includes an arrangement whereby the assemblage of the hanger parts is facilitated considerably in the original manufacture. With this preamble in mind, the objects of the invention are as follows:

First, to provide a trousers hanger wherein 15 a movable clamping bar works in conjunction with a fixed transverse or tie bar to suspend the trousers between them, a feature of especial importance comprising the flattening of the confronting sides of said bars to expand the contact 20 surface and produce a better grip on the garment than if said bars were merely rounded, as well as to avoid the objectionable crease which occurs 25 from the latter.

Second, to provide a special construction of 30 clamping bar whereby said bar can be permanently affixed to the frame after the latter has been completely formed.

Third, to provide a trousers hanger wherein the clamping bar is slotted at each of its ends, the slot at one end being excessively long to permit the preliminary mounting of the clamping bar upon the sides of the wire frame, whereupon the 35 stay pin is driven through to shorten the excessively long slot to the size whereat end movement of the clamping bar is prohibited.

Other objects and advantages will appear in 40 the following specification, reference being had to the accompanying drawing, in which:

Figure 1 is a side elevation of the improved trousers hanger, also illustrating its manner of use.

Figure 2 is a cross section taken on the line 45 2—2 of Fig. 1.

Figure 3 is a perspective view of the hanger.

Figure 4 is a cross section taken on the line 4—4 of Fig. 3.

Figure 5 is a detail perspective view of one end 50 of the clamping bar, particularly illustrating the excessively long slot and the stay pin.

The garment hanger is generally designated 1. It comprises a rectangular wire frame consisting of the sides 2, the supporting bar 3 which connects the sides 2 at the bottoms, and the top cross

bar 4 which connects the sides at the tops. Said cross bar has the hook 5 made integrally with it. The supporting bar 3 has a medial indentation 6 for the purpose of accommodating the extra thickness of the seams 7 of the trousers legs 8 5 when the garment is inserted in the manner shown in Figs. 1 and 2.

A clamping bar 9 is movably carried by the hanger frame. Said bar is usually made of wood. It is desirably made much larger than the supporting bar 3 in cross sectional size. Said bar is also desirably made cross sectionally round so that the portion 10 of the garment (Fig. 2) will lie upon the bar on an easy curve and thus avoid imparting a crease. To the latter end the confronting surfaces of the bars 3, 9, are flattened at 11, 12. This flattening produces a flat-sided passage for the adjacent portion of the garment. Notwithstanding the fact that the bar 9 is much larger than the bar 3, it would play its part in 20 leaving a crease where it bears down on the medially situated portion of the garment.

By flattening the confronting faces as stated, the possibility of making the crease is greatly minimized, and, in fact, eliminated when the garment is not left hanging too long. It is readily seen from Fig. 2 that in applying the garment portion 10 over the bars 3, 9 from opposite sides, that a very effective support is produced.

A feature of no little importance relates to the clamping bar 9. This bar is intended to be fitted into the hanger frame after the latter has been manufactured completely in its rectangular shape. For the purpose in mind the clamping bar 9 is 35 slotted at 13, 14 at its ends (Fig. 4), the slot 14 being excessively long. The purpose of this provision is to provide sufficient slot space at 14 to enable the bar end 15 (Fig. 4) to be swung around into position to the inside of the side 2 at the 40 right of the frame. It is readily seen that this can be accomplished by moving the clamping bar 9 over far enough to make the side 2 at the left rest at the bottom of the long slot 14. Said bottom then becomes the fulcrum for the foregoing 45 swinging of the clamping bar 9 into position.

After this has been achieved the clamping bar 9 is moved far enough to the right to secure an easy sliding fit of the base of the slot 13 with the side 2 at the right whereupon a stay pin 16 is 50 driven through that end of the bar 9 having the slot 14, and in such a position across said slot as to again secure an easy sliding fit of the stay pin with the side 2 at the left. Said pin is intended to remain permanently but it would be possible 55

to drive it out with a pointed instrument if the occasion should ever arise to take the clamping bar 9 out.

The latter provision is important from the standpoint of manufacture of the trousers hanger. The devices can be produced quickly in lots if there is no necessity for having to embody the movable clamping bar 9. The rectangular forms are transferred to a worker other than the one who makes them, and by inserting the long slot 14 all the way it becomes an easy matter to quickly emplace the clamping bar 9 and secure it in its movable position by driving the stay pin 16 across.

15 I claim:

1. A trousers hanger comprising a wire frame including a pair of sides and a connecting supporting bar, a clamping bar working in conjunction with said supporting bar, the ends of the clamping bar having slots of which one is longer than the other to provide for a sufficient end motion of the long slot along one of the sides to permit the emplacement of the other slotted end upon the other side, a stay pin driven across

said long slot to shorten the effective length thereof and prevent further end movement of the clamping bar, said bars being adapted to have the trousers legs applied therearound, said supporting bar having an indentation for the trousers seam, and both bars being flattened on their confronting sides to broaden the contact surfaces thereof against said legs. 5

2. For use in conjunction with a closed wire frame having parallel sides, a clamping bar to be 10 movably carried by said frame, the ends of said bar being slotted and one of the slots being longer than the other, the distance between the bottom of the long slot and the opposite end of the clamping bar being less than the distance between the parallel sides to permit swinging said opposite end into the frame for alining the respective slot with the respective side, the other side serving as a fulcrum against the bottom of said long slot, and a stay pin adapted to be 15 driven across the long slot to shorten the effective length thereof and prevent end movement of the clamping bar.

JOSEPH D. MCOSKER.
